UNITED STATES PATENT OFFICE.

JOHN A. KLINE, OF ROYER'S FORD, PENNSYLVANIA, ASSIGNOR OF ONE-HALF TO LEWIS BUCKWALTER, OF SAME PLACE.

LOCK-HINGE.

SPECIFICATION forming part of Letters Patent No. 288,345, dated November 13, 1883.

Application filed August 1, 1883. (Model.)

To all whom it may concern:

Be it known that I, JOHN A. KLINE, a citizen of the United States, residing at Royer's Ford, in the county of Montgomery and State of Pennsylvania, have invented a new and useful Shutter-Hinge, of which the following is a specification, reference being had to the accompanying drawings.

This invention relates to hinges for window blinds, shutters, and the like; and it has for its object to produce a lock-hinge which shall be absolutely wind-proof, or incapable of being closed by the force of the wind against the blind or shutter which may be hinged thereby, but which may be readily closed, when it shall be desired to do so, by means of a simple contrivance attached to or forming part of the device.

My invention therefore consists in the improved construction and arrangement of parts, which will be hereinafter fully described, and particularly pointed out in the claim.

In the drawings hereto annexed, Figure 1 is a perspective view, showing my improved hinge open. Fig. 2 is a rear view of the same. Fig. 3 is a perspective view, showing the hinge in position for being closed. Fig. 4 is a side view, showing the hinge closed; and Fig. 5 is a detail view, showing in perspective the several parts composing my improved hinge detached from each other.

The same letters refer to the same parts in all the figures.

A and B designate the leaves of my improved hinge, which may be cast or otherwise constructed of iron or other suitable metal. The leaf A is constructed with the cylindrical body C, from which the pintle D projects upwardly, as shown in the drawings. The upper side of the cylinder C, in front and in rear of the pintle, is beveled, so as to form a double inclined track, E E.

F is a lug or stop projecting laterally from the upper end of the cylinder C.

G is a lug or stop projecting forwardly from the upper end of the cylinder.

H is a beveled or inclined lug formed upon the rear side of the leaf A, adjoining the upper end of the cylinder C, as shown.

I is a ring adjusted upon the upper bevel

end of the cylinder C, and having its under side beveled to correspond. The ring I is provided with an operating arm or handle, J, having a downwardly-projecting stop-lug, K.

The leaf B of the hinge is provided with the eye L, by which it is hinged upon the pintle D above the ring I, the upper edge of which is flush with the upper edge of the cylinder C proper. Projecting laterally from the eye L is a lug, M, which is beveled upon the under side.

In operation, when the shutter or blind, which is attached to the leaf B, is opened, the leaf B will open smoothly until the lug M reaches the lug H of leaf A. The leaf B (carrying the shutter) will then be forced slightly in an upward direction until the lug M drops down in front of the leaf A, where it forms a stop that prevents the leaf B from closing. At the same time the body of the leaf B reaches and abuts against the stop-lug F, preventing the said leaf B from being opened farther. It will thus be seen that the leaf B and the shutter attached thereto will be held or retained with absolute security in an open position. In order to close the shutter it is only necessary to turn the ring I, by means of the handle J, to the position shown in Fig. 3 of the drawings. By thus turning the said ring it will travel up the inclined or beveled tracks E E, thus lifting or raising the leaf B until the lug M may pass over the upper edge of the lug H, thus permitting the leaf B to be easily closed. The arm or handle J of the ring I will be folded between the leaves A and B.

I am aware that lock-hinges have been constructed previous to my invention comprising a beveled track for the upper leaf and suitable stop-lugs; also, that lock-hinges have been equipped with beveled rings interposed between the leaves for unlocking. Such construction I do not, therefore, broadly claim.

I claim as my invention and desire to secure by Letters Patent of the United States—

The combination, in a lock-hinge, of the leaf A, having the cylinder C beveled on top, so as to form the double track E E, the ring I, having its under side beveled to correspond

with the track E E, and provided with the arm or handle J, the stop-lug G, projecting forwardly from the cylinder C, and the leaf B, having the laterally-projecting locking-lug M, substantially as and for the purpose set forth.

In testimony that I claim the foregoing as

my own I have hereto affixed my signature in presence of two witnesses.

JOHN A. KLINE.
